US00D996398S

(12) **United States Design Patent** (10) **Patent No.:** **US D996,398 S**
Zhan (45) **Date of Patent:** **** Aug. 22, 2023**

(54) **SOUND PRODUCING DEVICE**

(71) Applicant: **Shu-Ying Zhan**, Taipei (TW)

(72) Inventor: **Shu-Ying Zhan**, Taipei (TW)

(**) Term: **15 Years**

(21) Appl. No.: **29/761,553**

(22) Filed: **Dec. 10, 2020**

(51) **LOC (14) Cl.** **14-01**

(52) **U.S. Cl.**

USPC **D14/222**

(57) **CLAIM**

The ornamental design for a sound producing device, as shown and described.

DESCRIPTION

FIG. 1 is a perspective view of a sound producing device showing my new design;

FIG. 2 is a front elevation view of the sound producing device;

FIG. 3 is a rear elevation view of the sound producing device;

FIG. 4 is a left side elevation view of the sound producing device;

FIG. 5 is a right-side elevation view of the sound producing device;

FIG. 6 is a top plan view of the sound producing device; and,

FIG. 7 is a bottom plan view of the sound producing device.

1 Claim, 5 Drawing Sheets
